KEY FOR LOCKS

Samuel J. Holtzman, 8201 Symphony Drive,
Baltimore, Md.

Filed Oct. 23, 1963, Ser. No. 77,117

Term of patent 14 years

(Cl. D50—4)

FIG. 1 is a side elevational view of a key for locks embodying my new design;

FIG. 2 is an edge elevational view as seen from the right of FIG. 1, and

FIG. 3 is a side elevational view showing the side opposite that seen in FIG. 1.

The dominant features of my design reside in the portions shown in full lines.

I claim:

The ornamental design for a key for locks, as shown and described.
